HORACE R. WHITTIER, OF PLYMOUTH, CONNECTICUT.

OVEN THERMOMETER.

Application filed April 23, 1921, Serial No. 463,822. Renewed September 16, 1922. Serial No. 588,730.

To all whom it may concern:

Be it known that I, HORACE R. WHITTIER, a citizen of the United States, residing at 5 Plymouth, in the county of Litchfield and State of Connecticut, have invented a new and useful Improvement in Oven Thermometers, of which the following is a specification.

This invention relates to the class of thermometer in which the temperature indication is made by a pointer which is oscillated by the expansion and contraction of a circular member formed of thermoresponsive metal.

15 The object of the invention is to provide a thermometer of this type in which the active mechanism is very simple and cheap to construct and assemble and which will operate the pointer steadily and uniformly 20 according to the degrees of heat during all portions of its path.

This object is attained by loosely mounting the thermostatic strip that is connected with the pointer upon a bridge or spindle 25 holder so that it is free to expand and contract according to the temperature uniformly in all positions, that is, the strip is only influenced by the temperature and is at no time required to overcome tension or 30 mechanical resistance as would be the case if the strip was tightly fixed at one end.

In the accompanying drawings Fig. 1 shows a plan of the casing and active mechanism of a thermometer which embodies the 35 invention. Fig. 2 shows a section on the plane indicated by the dotted line 2—2 on Fig. 1.

The casing comprises a flat back plate 1, designed to be secured to the wall of the 40 oven or other part of the chamber, the temperature of which is to be indicated, and a cylindrical side wall 2, which with the back plate and cover that is omitted, surrounds and encloses the active mechanism.

45 The active mechanism is mounted on the bridge plate 3 that is fastened to the inside of the back plate by rivets or other convenient means. The spindle 4 with the indicating pointer 5 is rotarily mounted in a raised portion of the bridge and has its lower end set into a bushing 6, fastened in the back plate. Projecting upward from the bridge 50 is a post 7 and loosely hinged on this post so that it is free to swing is one end of the thermoresponsive strip 8 that is curved and

is made of common thermoresponsive metal, the opposite sides of which have different coefficients of expansion. The other ends of the thermoresponsive strip are hinged to a pin 9 that projects from the arm 10 which 60 is fixed to the pointer spindle. This arm 10 is provided with a number of holes 11, into either of which the pin 9 may be set for calibrating the device according to the required conditions.

65 The curved form of the thermostatic strip provides a greater degree of expansion than a straight strip and by reason of the loose connections of the strip at its ends it may swing and assume a natural position as the 70 curvature changes during expansion and contraction and thus there is no tendency of mechanical strains to resist the change of shape of the strip, a condition which would result if the strip were rigidly connected to 75 its support as in prior structures of this type. Furthermore, this arrangement permits the strip to be directly connected with the arm projecting from the spindle and eliminates the necessity of interposing a 80 link connection. In making this device the parts are all assembled on the bridge plate and then the plate is simply inserted into the casing and fastened in position.

The invention claimed is:

1. A thermometer comprising a casing, a 85 plate secured to the inside of the casing, a pointer spindle supported by the plate, an arm fixed to the spindle, a post projecting from the plate parallel with the spindle, a pin projecting from the arm parallel with the post, and a curved thermo-responsive strip with one end loosely hinged on the post and the other end loosely hinged on the pin whereby the strip may turn freely on 90 the post and pin and expand and contract uniformly in all positions under the varying temperature conditions.

95 2. A thermometer comprising a casing, a plate secured to the inside of the casing, a pointer spindle supported by the plate, an arm with perforations fixed to the spindle, a post projecting from the plate parallel with the spindle, a curved thermo-responsive strip with one end loosely hinged on the post and a pin loosely hinged to the other end of the thermo-responsive strip, said pin being 100 adapted to be inserted into either of the perforations of said arm.

HORACE R. WHITTIER.
